UNITED STATES PATENT OFFICE.

CHARLES A. LANG, OF ST. LOUIS, MISSOURI.

PAPER-DAMPENING MACHINE.

SPECIFICATION forming part of Letters Patent No. 695,216, dated March 11, 1902.

Application filed June 3, 1901. Serial No. 62,893. (No model.)

To all whom it may concern:

Be it known that I, CHARLES A. LANG, of the city of St. Louis, State of Missouri, have invented certain new and useful Improvements 5 in Paper-Dampening Machines, of which the following is a full, clear, and exact description, reference being had to the accompanying drawings, forming a part hereof.

This invention relates to paper-dampening 10 machines; and it consists of the novel construction, combination, and arrangement of parts hereinafter shown, described, and claimed.

Figure 1 is a rear end elevation of my improved machine. Fig. 2 is a plan view. Fig. 3 is a view showing one side. Fig. 4 is a view showing the side opposite from that shown in Fig. 3. Fig. 5 is a longitudinal section taken approximately through the center of the machine and showing the arrangement of the different parts. Fig. 6 is an enlarged detail view showing the devices by which the edge of the paper is held upon the surface of the rotary drum. Fig. 7 is a detail view showing the location and arrangement of the shaft, to which is connected one end of a reversible 25 section of absorbent cloth. Fig. 8 is a detail view showing the devices by which the clamping attachments are operated.

30 In the construction of my improved machine I provide the end frames 1, which support a table or inclined platform 2, sloping from the front toward the rear of the machine and consisting of two parts, the rear part 3 being hinged, so that it may be raised or lowered to afford access to the mechanism supported below it. A rotary drum 4 is supported between the side frames 1, and the upper surface of said frame is adjacent to the 35 rear edge of the part 3 of the table. A longitudinal groove 5 is formed in the drum 4, and a rod or shaft 6 is carried by the ends of the drum within the said groove 5, and a series of curved fingers 7 are carried at intervals by the said rod 6. The said rod 6 is turned when the drum is rotated so that the ends thereof bear upon the surface of the drum, as shown in Fig. 6; but the moment the groove 5 passes beyond the lower edge of the part 3 of the table the said rod is turned to raise the fingers to a vertical position, as shown in Fig. 5. Upon one end of the said rod 6 is a small

gear 8. An arm 9, carrying a gear-sector 10, is pivoted to the end of the drum 4, and a small roller 11 is carried by the inner end of the 55 arm 9 and operates upon the periphery of the cam 12, fixed to the end frame 1. While the drum is rotating the roller 11 moves over the surface of the cam 12, and thereby operates the arm 9 and the sector 10, which is in 60 mesh with the gear 8, thereby operating the rod 6 to move the fingers 7 into the position shown in Fig. 6. The arrangement of this cam 12 is such as to permit the rod 6 to turn and raise the fingers 7 to a vertical position when 65 the said fingers have passed beyond the lower edge of the part 3 of the table. These fingers are slightly raised to release the edge of the paper to permit the latter to be carried away from the drum by the carrying-ropes, 70 which I will presently describe. The fingers, however, are not entirely raised to a vertical position till after the fingers have passed beyond the edge of the part 3 of the table.

In the side of the drum 4, opposite from 75 the groove 5, is formed a second groove 13, in which is carried a rod or shaft 14, held from turning by means of a ratchet-wheel 15 and a pawl 16. A section 17 of rubber is attached to the rod 14, and the said rubber extends around the surface of the drum to the groove 5, where it may be attached to the pins or projections 18, carried within the said groove 5.

19 indicates a rod which is supported by 85 the frames above the drum 4, and a number of arms 20 are carried by the said rod 19, the said arms 20 being bent into suitable shape and having their ends terminating adjacent to the surface of the drum 4, thereby forming 90 stops or gages for the paper as it is fed from the table to the drum and holding the paper until the fingers 7 have been operated to bear upon the paper in order to hold it while the drum is rotating. A number of 95 curved arms 21 are supported at the rear side of the drum 4 and form guides to hold the free end of the paper in position while it is being carried around by the drum.

22 indicates a trough or basin adapted to 100 contain water and supported below the drum 4, the lower side of the drum extending into the said trough or basin, so that it will become dampened when rotated. A roller 23 is

- supported by the frames 1 within the trough or basin 22 and upholds the free end of the paper after it has passed beyond the ends of the arms 21. A roller 24 is supported above the front side of the trough or basin 22 and serves to remove the excess water or moisture from the paper as it is carried upwardly out of the said trough or basin by the drum. A shaft 25 is supported by the side frames 1 above the roller 24, and a similar shaft 26 is supported by the said side frames below and in front of the said shaft 25. A number of sheaves or pulleys 27 are carried on each of the shafts 25 and 26, and ropes or belts 28 are passed around the said sheaves or pulleys. A power-shaft 29 is supported at one side of the machine, to be driven by belts applied to pulleys 30, fixed thereon. A gear 31 is carried by the said shaft 29 and meshes with the large gear 32, attached to one of the trunnions rigid with the drum 4, thereby rotating the said drum when the shaft 29 is driven. A gear 33 is fixed to the end of the roller 24 and meshes with the gear 32, and thereby rotates the said roller 24. A sheave or pulley 34 is supported adjacent to the gear 32, and a rope or belt 35 passes around the said sheave or pulley and around a pulley 36, carried by the end of the shaft 25, thereby rotating the said shaft 25 and moving the ropes or belts 28. A roller 37 is supported by the side frames 1 above the shaft 25 and rests upon the surface of the drum 4 and serves to remove all excess moisture.
- 35 A transverse rod 38 is supported by the frames 1, and a spring-held pulley 39 is supported by the said rod 38, and a belt or rope 40 passes around the said pulley 39 and around the drum 4, as shown in Fig. 5, and the said belt or rope serves to guide the upper edge of the paper over the pulleys 27 onto the belts or ropes 28, whereby the paper will be carried downwardly and placed upon a number of arms, by means of which it is delivered to an adjacent platform.
- 40 A rod or shaft 41 is supported in front of the shaft 26, and a series of arms 42 are fixed upon the said shaft, and the said arms extend upwardly at an incline, their upper ends resting between the rods 28. A gear-wheel 43 is fixed to the end of the shaft 41, and a rack 44 is in mesh with the gear 43, said rack being fixed to the end of an arm 45, and the said arm is pivoted to the frame 1. An arm 46 is pivoted to the frame 1 above the arm 45 and is connected to the said arm 45 by a rod 47. The rear end of the arm 46 carries a small roller 48, which rides upon the cam 49, the latter being fixed to one of the trunnions of the drum 4 and turning as the said drum rotates. By this means the rear end of the arm 46 will be raised once during each revolution of the drum 4, which will operate the arm 45 and the rack 44 and rotate the shaft 41 and operate the arms 42 to raise the paper from the ropes or belts 28 and deliver the same onto an adjacent platform 50. The

stops or gages 20 are raised at the required time to permit the paper to pass by means of the arm 51, which rides upon the cam 52, carried by the end of the drum 4.

The operation is as follows: The paper is delivered onto the table 2 and passed rearwardly until the lower edge thereof engages against the stops or gages 20. The drum 4 in the meantime is rotating, and the fingers 7 will be operated by the rack 10 to clamp upon the edge of the paper and hold the same on the drum while the latter is rotating. The stops 20 are now raised by the arm 51, which is operated by the cam 52 to permit the paper to pass. The paper is carried around by the drum and is passed through the water in the trough or basin 22, whereby it will be dampened. The free edge of the paper will be upheld by the arms 21 and by the roller 23. The paper will be carried upwardly out of the trough or basin 22, and excess water and moisture will be removed therefrom by the roller 24. When the fingers 7 have passed above the sheaves or pulleys 27 on the shaft 25, they permit the paper to pass therefrom and be guided outwardly by the rope or belt 40 and delivered onto the ropes or belts 28, whereby it will be carried downwardly above the arms 42. The arm 49 now raises the rear end of the arm 46, which also operates the arm 45 and rotates the shaft 41. This raises the arms 42, which remove the paper from the ropes 28 and deliver the same onto the platform 50. Thus it is seen that one sheet of paper is moistened by each revolution of the drum 4 and is also delivered from the drum onto the platform, from which it may be removed to any suitable place.

I claim—

1. A machine for dampening paper, consisting of a drum, a liquid-receptacle located below the drum, means for rotating the drum, means for holding the paper upon the drum so that it will be carried around therewith and passed through the liquid-receptacle when the drum is rotated, and means for automatically releasing the paper from the drum, substantially as specified.

2. A machine for dampening paper, consisting of a rotary drum, a liquid-receptacle supported below the drum and inclosing a part of the same, means carried by the drum for holding the paper upon the drum so that it will be carried around thereby and passed through the liquid in the receptacle, means for removing the excess moisture from the paper, means for automatically releasing the paper after it has been dampened, means for removing the paper from the drum, means for delivering the paper onto a suitable support, and means for removing the excess moisture from the surface of the drum, substantially as specified.

3. A machine for dampening paper, consisting of a drum, a liquid-receptacle located below the drum, means for rotating the drum, means for holding the paper upon the drum

so that it will be carried around therewith when the drum is rotated, and means for automatically releasing the paper from the drum, substantially as specified.

5 4. A machine for dampening paper, consisting of a rotary drum, a liquid-receptacle supported below the drum, means carried thereby for holding the paper so that the paper will be carried around as the drum rotates and passed through the liquid in the receptacle, means for automatically releasing the paper after it has been passed through the liquid, and means for delivering the paper to a suitable support, substantially as specified.

15 5. A machine for dampening paper, consisting of a drum adapted to be rotated, a liquid-receptacle supported below the drum, fingers for holding the paper on the drum, means for automatically operating the fingers to release the paper after it has been moistened, and means for delivering the paper to a suitable support, substantially as specified.

25 6. A machine for dampening paper, consisting of a drum, a liquid-receptacle below the drum and inclosing a part of the drum, fingers carried by said drum for holding the paper thereon, means for rotating the drum, and means for automatically removing the paper from the drum after it has been dampened.

30 7. A machine for dampening paper, con-

sisting of a drum, means for rotating the drum, a series of fingers carried by the drum, means for operating the fingers to hold the paper upon the surface of the drum, a trough or basin supported adjacent to the drum and adapted to contain water whereby the paper will be dampened, means for removing the excess moisture from the paper, means for operating the said fingers to release the paper, a series of arms, and means for operating the said arms to deliver the paper away from the drum, substantially as specified.

35 8. A machine for dampening paper, consisting of a rotary drum adapted to support the paper, a trough or basin supported adjacent to the drum and within which a portion of the drum extends so that the paper will be dampened while the drum rotates, means for removing the excess moisture from the paper, a series of pulleys supported adjacent to the drum, ropes operating around said pulleys, means whereby the paper will be guided onto said ropes, a series of arms supported between the said ropes and pulleys, and means for operating the said arms to remove the paper from the said ropes, substantially as specified.

40 In testimony whereof I affix my signature in presence of two witnesses.
